UNITED STATES PATENT OFFICE.

DAVID GERBER, OF BALTIMORE, MARYLAND.

DESIGN FOR AN ICE-CREAM CONE.

Application filed August 10, 1928. Serial No. 27,770. Term of patent $3\frac{1}{2}$ years.

To all whom it may concern:

Be it known that I, DAVID GERBER, a citizen of the United States, residing in the city of Baltimore and State of Maryland, have invented a new, original, and ornamental Design for Ice-Cream Cones, of which the following is a specification, reference being had to the accompanying drawing, forming a part thereof.

The drawing is a view of an ice cream cone showing my new design.

I claim:

The ornamental design for an ice cream cone as shown.

DAVID GERBER.
